MULTIPLE UNIT TOWNHOUSE

Peter H. Edwards, Upper Arlington, and Harvey R. Geiger and William Byron Ireland, Columbus, Ohio, assignors to Multicon Properties, Inc., Columbus, Ohio

Filed July 2, 1971, Ser. No. 159,156

Term of patent 14 years

Int. Cl. D25—03

U.S. Cl. D13—1 A

FIG. 1 is a front elevational view of a multiple unit townhouse showing our new design;

FIG. 2 is a rear elevational view;

FIG. 3 is a top plan view;

FIG. 4 is an end elevational view on a slightly enlarged scale looking toward the left-hand end of the multiple unit townhouse as shown in FIG. 1; and

FIG. 5 is an end elevational view of the opposite end of the multiple unit townhouse.

We claim:

The ornamental design for a multiple unit townhouse, substantially as shown.
